UNITED STATES PATENT OFFICE.

WILLIAM F. COOPER, OF NORWALK, OHIO.

VALVE FOR PLAYER-PIANO FEEDERS.

1,355,941.

Specification of Letters Patent. Patented Oct. 19, 1920.

Application filed December 17, 1917. Serial No. 207,437.

To all whom it may concern:

Be it known that I, WILLIAM F. COOPER, a citizen of the United States, residing at Norwalk, in the county of Huron and State 5 of Ohio, have invented a certain new and useful Improvement in Valves for Player-Piano Feeders, of which the following is a full, clear, concise, and exact description, reference being had to the accompanying 10 drawings, forming a part of this specification.

The present invention relates to valves for player piano feeders.

The primary object of the invention is to 15 provide a valve for pneumatic feeders which will be absolutely silent in operation. Additional objects are to provide a valve which will not be susceptible to leakage due to climatic conditions, and which will operate 20 with ease and quickness at all suction pressures, tending toward an increase in the efficiency of the feeders and a decrease in the power necessary to their operation.

The feeders in a player piano function to 25 supply suction pressure to the pneumatic action, to the air motor, and to all the manual and automatic controls in the player piano. These mechanisms are constantly changing in operation and impose a variable 30 suction demand on the feeders, particularly in player pianos not having reservoir bellows or the like. Accordingly, the valves in the feeders must be capable of controlling effectively and silently a flow of air under- 35 going large and sudden changes in volume and pressure.

In the accompanying drawings I have 40 illustrated my improved valve as applied to the feeders in a motor driven suction pump, but it will be apparent that the valve is also applicable to pedal operated feeders. In the following specification I have illustrated and described one particular embodiment 45 of my improved valve, but I intend that other embodiments and modifications of the same shall come within the spirit and scope of the invention.

Figure 1 is an elevational view of a suction pump showing part of the casing 50 broken away and one of the feeders in cross section.

Fig. 2 is an enlarged fragmentary section of one of the feeder boards showing my improved valve therein and

Fig. 3 is a similar section showing the 55 general type of valve heretofore employed.

The pump 1 is substantially square, and has four feeders 2 mounted within the pump in quadrangular form. An electric motor 3 supplies power for the operation of the 60 feeders which is transmitted thereto through the pulley 4, the crank 5, crank block 6 and the flexible fabric connectors 7, which are attached to blocks 7' secured to the movable leaves of the feeders 2. The feeders 2 are 65 of general construction, comprising the fixed and movable leaves or boards 8 and 9, respectively, which are joined by fabric sides 11. A suction channel 12 communicating with the expression mechanism and controls of the player, extends around on all sides of the pump and is arranged to be exhausted by the feeders 2. The inlet valves for the feeders are mounted in the fixed boards 8, and afford an intake between the 70 channel 12 and the interior of the feeder. The exhaust valves are mounted in the movable board 9, and afford an outlet between the interior of the feeder and the interior of the pump casing from whence the air per- 75 meates to the exterior through the felt strips 13 in the sides of the pump casing.

The valves for these feeders have heretofore been of the general construction illustrated in Fig. 3. The board 15 which corresponds either to one of the feeder boards 8 or 9 of the above description, or to a special panel applied thereto, has valve openings 16-16 therethrough. These valve openings are usually contiguously arranged parallel to the length of the feeder board 15 and are covered on one side of the feeder board by a long strip of pliable leather 17, which is glued or tacked across its two narrow ends to the board as shown at 18. This strip of 90 leather has a check valve action over the valve openings 16-16, the pliancy of the leather strip permitting the flow of air up from the openings 16 beneath the two free edges of the strip but preventing a counter 95 flow of air by sucking taut over the openings 16.

I find that frequently these valves will emit a popping noise when the feeders are working at a high suction pressure. I have experimented with numerous types of pneumatic valves and have found that these objectionable noises are attributable mainly to the pouching diaphragm action of the leather or fabric strip 17 over the valve openings 16. It will be seen that the strip 17 must necessarily be very pliable to operate smoothly and quickly, so that there will be no wasteful expenditure of power in the operation of the feeders. The pliancy of the leather which is so essential to the effective operation of this type of valve, results in the detrimental action above referred to. The leather strip 17 has a pronounced tendency to flex inwardly into each of the valve openings 16, as illustrated in dotted lines in Fig. 3, due to the difference of pressures acting upon opposite sides of the strip. Valves having corrective means to prevent this inward flexure are not productive of this disagreeable popping noise.

Another detrimental characteristic of this type of valve is the tendency of the free edges of the leather strip to curl up, due to the aging and drying of the leather, whereby a portion of the valve opening is exposed or an insufficient area of engagement is had, between the leather strip and the surface of the board, resulting in a leaky valve. This latter characteristic is curable to some extent by securing transverse ribs 20 to the back of the strip 17 to prevent curling of the same, but these add considerably to the inertia of the valve.

To obviate this objectionable curling and pouching of the valve leather I contemplate stiffening that portion of the valve immediately over the valve openings without subtracting from the flexibility of the remaining portion of the strip. A particular embodiment of this conception is illustrated in Fig. 2.

The valve openings 22 are concentric with depressions or valve chambers 23, formed in the face of the board 24. Small metallic ferrules 25 are driven down part way into the valve openings 22, the projecting edge of the ferrule presenting a sharp clean valve seat to be engaged by the small wooden disks or buttons 26. These buttons are provided with leather facings 27, glued thereto, which secure a tight fit with the edges of the ferrules 25, when the buttons are down thereupon. The buttons 26 are glued at 28 to the strip 29. This strip is preferably of felt or some flexible material of very loose texture, so that it will be highly permeable to air. The strip is glued or tacked along its perimeter to the face of the board 24, as shown at 30, the air that issues from beneath the buttons 26 passing directly through the felt. This is the preferred means for sup-

porting the buttons 26, though other means may be employed, as for instance, a strip of leather similar to the strip 17 of Fig. 2 or individual strips to which the buttons 26 are secured, the air then escaping around 70 the edges of the strip.

The button is preferably made of wood as described, but it will be apparent that I can substitute a stiff piece of leather or other material having the necessary rigidity 75 to resist flexing under high suction pressures. I find the use of the ferrule 25 advantageous in securing a tight valve closure though it can be dispensed with by having the buttons 26 seat on the bottom of the 80 valve chamber 23 directly over the valve opening 22.

The advantages resulting from the combination of the relatively stiff valve member and the relatively pliant strip for supporting and guiding the valve member will be apparent. The button 26 is not subject to the objectionable pouching action or the tendency to curl at the edges as is the leather strip 17 of the prior art. The felt strip 90 29 supports and guides the valve button 26, but by virtue of its extreme pliancy it does not retard the button in its movement. Moreover the felt tends to muffle any slight vibration of the button.

In its broad conception the invention discloses a valve for pneumatic feeders which will operate quickly and easily and which will not pouch or flex into the valve opening and I intend that the appended claims 100 be construed in the light of this disclosure.

I claim:

1. In combination, a feeder board, said feeder board having an opening therethrough, a ferrule in said opening, a strip of flexible material secured to said feeder board and a relatively stiff valve member secured to said flexible strip and seated on said ferrule.

2. In combination, a feeder board, said feeder board having a valve opening therethrough, a ferrule in said valve opening, a strip of permeable felt secured to said feeder board, and a relatively stiff valve button secured to said felt strip and seated on said ferrule.

3. In a valve for pneumatic mechanism, a valve opening subjected to suction, a valve member adapted to cover said opening, and a strip of pliant fabric for supporting said valve member, said valve member having a relatively stiff body portion to prevent flexing of the same into said valve opening under the influence of said suction.

4. In a valve for pneumatic mechanisms, the combination of a valve opening subjected to suction, and a valve member covering said opening, said valve member comprising a non-flexible material adapted to contact directly with said valve opening to 130

prevent flexing of the same into said valve opening under the influence of said suction.

5. In a valve for pneumatic feeders, a valve opening subjected to suction, valve means covering said opening, said valve means comprising a section of pliant material, and a valve member of rigid, non-flexible material adapted to contact directly

with said valve opening to prevent flexing of said valve means into said valve opening 10 under the influence of said suction.

In witness whereof I hereunto subscribe my name this 1st day of December, A. D. 1917.

WILLIAM F. COOPER.
